UNITED STATES PATENT OFFICE.

ARTHUR LEE LIGON, OF PECOS, TEXAS.

BLACKSMITH'S TOOL SET.

1,142,447.

Specification of Letters Patent.

Patented June 8, 1915.

Application filed October 3, 1914. Serial No. 864,886.

To all whom it may concern:

Be it known that I, ARTHUR LEE LIGON, a citizen of the United States of America, residing at Pecos, in the county of Reeves 5 and State of Texas, have invented certain new and useful Improvements in Blacksmiths' Tool Sets, of which the following is a specification, reference being had therein to the accompanying drawing.

10 This invention relates to a blacksmith's tool and has for its object the production of a simple and efficient holder which is adapted to support a tool of the desired construction or shape for accomplishing the desired 15 result.

Another object of this invention is the production of a simple and efficient handle, whereby the tool adapted to be carried thereby may be readily and efficiently removed 20 from the handle without the necessity of requiring the operator to place his hand upon the tool itself.

Other objects and advantages of the present invention will appear throughout the 25 following specification and claims.

In the accompanying drawings:—Figure 1 is a side elevation of the handle showing one of the tools applied thereto. Fig. 2 is a central longitudinal sectional view through 30 the forward portion of the handle showing a tool carried thereby. Fig. 3 is a horizontal sectional view through the handle showing the same in a closed position. Fig. 4 is a top plan view of the forward portion of 35 the handle. Fig. 5 is a section taken on line 5—5, of Fig. 1 showing the clamping ring in section. Fig. 6 is a section taken on line 6—6, of Fig. 1. Fig. 7 is a section taken on line 7—7, of Fig. 1. Fig. 8 is a detail perspective of the clamping ring used in connection with the present invention. Fig. 9 40 is a section taken on line 9—9, of Fig. 1. Fig. 10 is a perspective view of the stop knob carried by the handle of the device for 45 limiting the rearward sliding movement of the clamping ring. Fig. 11 is a side elevation of one of the tools which may be used in connection with the present invention.

It should be understood that the present 50 device has special reference to a handle which is adapted to engage or support any number of different kind of shaped tools, and that these tools may be readily placed upon or disengaged from the handle when 55 so desired. It is not desired to limit the present application to any special form or

design of tool which may be carried by the handle, and it is desired to point out that any shape or desired form of tool may be mounted upon the handle.

By referring to the drawings it will be seen that 1 designates the shank of the tool which is provided with a semi-circular finger 2 having a centrally arranged beaded portion 3 formed thereon for the purpose of receiving the laterally extending teeth 4 of the tool 5 which is adapted to be carried by the shank of the handle. The shank 1 is provided with a swinging jaw 6, which jaw is pivotally mounted upon the shank 1 by 60 means of a pivot pin 7. The jaw 6 is provided with a projecting semi-circular knuckle 8 having a beaded portion 9 formed thereon of similar construction to the beaded portion 2 formed upon the finger 3 so as 65 to produce a semi-circular channel around the entire inner face of the fingers 2 and 8. The jaw 6 is provided with a rearwardly extending arm 10 which is provided with an inwardly bent end portion 11 as is clearly 70 illustrated in Fig. 3, which end portion is adapted to be engaged by the inwardly extending lug 12 of the clamping band or ring 13, which ring is adapted to slide upon the shank 1 as will be hereinafter more 75 clearly described. The finger 2 is provided with an inwardly extending lug 14 upon its inner face and this lug 14 is adapted to fit between two of the teeth 4 formed upon the tool 5 as is clearly illustrated in Fig. 80 90 for the purpose of locking the tool in a set position and preventing the accidental rotation of the tool 5 while the device is in operation. The shank 1 is provided with a rearwardly extending web portion 15, which 95 web portion is provided with laterally extending flanges 16 for constituting a pocket for receiving the wooden filler portion 17 of the handle. These wooden filler portions 17 are placed upon the web portion 15 and 100 between the flanges 16 and are firmly held in engagement therewith by means of the transversely extending rivets 18 as is illustrated in Fig. 7.

The shank 1 is provided with a pair of longitudinally extending grooves 19 along its sides, which grooves constitute track portions for receiving the inwardly extending beaded lugs 20 formed upon the inner face of the locking or clamping band 13 as is 110 clearly illustrated in Figs. 5 and 9. The clamping band 13 is also provided with a

binding lug 22 upon one of its side portions which extends at right angles to the beaded portions 20, and this binding lug 22 is provided with a beveled face 23 as is clearly illustrated in Fig. 8 for the purpose of riding upon the inwardly bent portion 11 of the inwardly extending arm 10, and thereby firmly clamp the fingers 2 and 8 together around the tool 5 which is adapted to be carried by the handle. As is clearly illustrated in Fig. 2, the shank 1 is provided with an elongated spring arm 24 which is fixedly secured to the inner portion of the shank by means of the rivets 25, and this spring arm 24 carries an outwardly extending stop knob 26 which is knurled or milled upon its upper face as indicated at 27 for the purpose of facilitating the operation of the stop knob 26. It should be understood that the binding or clamping ring 13 will be held against rearward movement upon the handle while the stop knob 26 is in the position shown in Fig. 2, but when this knob is forced inwardly, the ring 13 may be drawn over the knob so as to allow the ring to be moved rearwardly to a sufficient distance to allow the arm 10 to be swung outwardly and thereby permit the tool 5 to be disengaged from the handle. In this manner the handle may be operated so as to replace a tool in the handle when so desired, and by allowing the stop knob to remain in the position shown in Fig. 2, the clamping or binding ring 13 will not be permitted to pass to a position to allow the arm 10 to swing outwardly and cause the accidental dropping of the tool 5 from the handle.

It should be understood that any number of these handles may be employed when fixing up a blacksmith tool set for accommodating different size tools if so desired, and it should be further understood that any other desired changes or combinations of tools may be employed without departing from the spirit of the invention, so long as the device is confined within the scope of the appended claims.

Having thus described the invention what is claimed as new, is:—

1. A device of the class described comprising a shank, a jaw pivotally mounted thereon, tool gripping means carried by said jaw and shank, said jaw provided with a rearwardly extending arm having an inwardly bent portion, said arm adapted to be swung within said shank, said shank provided with a plurality of longitudinally extending grooves, a clamping band slidably mounted upon said shank and provided with a plurality of longitudinally extending lugs fitting within said grooves for limiting the

sliding movement of said band upon said shank, said shank provided with a binding lug adapted to travel upon said inwardly bent portion of said arm and firmly clamp 65 said jaw in a locked position upon said shank.

2. A device of the class described comprising a shank, a jaw pivotally mounted thereon, tool gripping means carried by said jaw and shank, said jaw provided with a rearwardly extending arm having an inwardly bent portion, said arm adapted to be swung within said shank, said shank provided with a plurality of longitudinally extending grooves, a clamping band slidably mounted upon said shank and provided with a plurality of longitudinally extending lugs fitting within said grooves for limiting the 70 sliding movement of said band upon said shank, said shank provided with a binding lug adapted to travel upon said inwardly bent portion of said arm and firmly clamp 75 said jaw in a locked position upon said shank, a stop lug secured to said shank and projecting through one of said grooves for 80 limiting the sliding movement of said clamping band in one direction upon said shank.

3. A device of the class described comprising a shank, a jaw pivotally mounted thereon, tool gripping means carried by said jaw and shank, said jaw provided with a rearwardly extending arm having an inwardly bent portion, said arm adapted to be swung within said shank, said shank provided with a plurality of longitudinally extending grooves, a clamping band slidably mounted upon said shank and provided with a plurality of longitudinally extending lugs fitting within said grooves for limiting the 90 sliding movement of said band upon said shank, said shank provided with a binding lug adapted to travel upon said inwardly bent portion of said arm and firmly clamp 95 said jaw in a locked position upon said shank, a stop lug provided with an elongated spring body secured to the inner face of said shank, said stop lug provided with an outwardly extending end, one of said 100 grooves provided with an aperture, said outwardly extending end of said stop lug passing through said aperture, and said stop lug adapted to be forced inwardly to permit said clamping band to be moved longitudinally 105 within said groove for permitting said arm 110 of said jaw to be swung outwardly.

In testimony whereof I hereunto affix my signature in presence of two witnesses.

ARTHUR LEE LIGON.
